UNITED STATES PATENT OFFICE

127,306

DESIGN FOR AN ASH TRAY

Jewell M. Pearce, Tulsa, Okla.

Application May 2, 1940, Serial No. 92,095

Term of patent 7 years

To whom it may concern:

Be it known that I, Jewell M. Pearce, a citizen of the United States, residing at 1731 North Cincinnati Avenue, in Tulsa, county of Tulsa, and State of Oklahoma, have invented a new, original, and ornamental Design for an Ash Tray, of which the following is a specification, reference being had to the accompanying drawing, forming part thereof.

Fig. 1 is a top perspective view of the ash tray showing my new design; and

Fig. 2 is a top perspective view of the removable grate forming a part of the design shown in Fig. 1.

I claim:

The ornamental design for an ash tray, as shown.

JEWELL M. PEARCE.
